US0D1087162S

(12) **United States Design Patent** (10) Patent No.: **US D1,087,162 S**
(45) Date of Patent: ** Aug. 5, 2025

(54) **COMPUTER SCREEN WITH GRAPHICAL USER INTERFACE**

(71) Applicant: **THE JAPAN STEEL WORKS, LTD.**, Tokyo (JP)

(72) Inventors: **Takayuki Yamazawa**, Tokyo (JP); **Tingbi Xiong**, Tokyo (JP); **Jun Suzuki**, Tokyo (JP)

(73) Assignee: **The Japan Steel Works, Ltd.**, Tokyo (JP)

(**) Term: **15 Years**

(21) Appl. No.: **35/521,370**

(22) Filed: **Jun. 16, 2023**

(80) **Hague Agreement Data**

Int. Filing Date: **Jun. 16, 2023**

Int. Reg. No.: **DM/232055**

Int. Reg. Date: **Jun. 16, 2023**

Int. Reg. Pub. Date: **Jun. 21, 2024**

(57) **CLAIM**

The ornamental design for a computer screen with graphical user interface as shown and described.

DESCRIPTION

The file of this patent contains at least one drawing/photograph executed in color. Copies of this patent with color drawing(s)/photograph(s) will be provided by the Office upon request and payment of the necessary fee.

1. Computer screen with graphical user interface

1.1 : Front view of an embodiment of a computer screen with graphical user interface

The outermost broken lines depict a computer screen or portion thereof that forms no part of the claimed design. The remaining broken lines illustrate portions of the graphical user interface that form no part of the claimed design.
